UNITED STATES PATENT OFFICE.

JAMES LUCK WARNER, OF TULSA, OKLAHOMA.

PLECTRUM FOR STRINGED INSTRUMENTS.

Application filed September 3, 1926. Serial No. 133,429.

This invention relates to a plectrum for stringed instruments, one of the objects being to provide a structure of this character constituting an efficient rest or support for the hand of the player and which holds the fingers so positioned that the device can be readily manipulated for the purpose of properly moving the pick across the selected string or strings.

- 10 With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed, without departing from the spirit of the invention.
- 15 In the accompanying drawings the preferred form of the invention has been shown.

In said drawings,

- Figure 1 is a plan view of a portion of the stringed instrument showing the present improvements applied thereto.

Figure 2 is a vertical longitudinal section through the plectrum attachment.

- Figure 3 is a section showing a slightly modified construction.

Referring to the figures by characters of reference 1 designates a bearing block adapted to be connected in any suitable manner to the rim R of the body of a stringed musical instrument. In the structure illustrated in Figures 1 and 2 a pivot pin 2 is extended from this block 1 and through one end of an arm 4. The pivot end portion of this arm has a recess 5 in its upper face for the reception of a wrist plate 6 having a rounded edge portion as shown and which is preferably held in position by the head 7 of the pivot pin 2. Extending laterally from the other end portion of the arm 4 is a finger plate 8 having shallow recesses 9 in its edges for the reception of the respective fingers so that the fingers of the hand using the plectrum will be held comfortably spaced at the proper distances to secure the best results.

An angular opening 10 is extended 50 through the arm 4 and the plates 8 and this opening receives a pick 11 pointed at both ends, as shown at 12 and held securely in place by a set screw 13.

In practice the hand of the player is 55 placed upon the arm 4 with the palm resting on the plate 8 and the wrist resting on the plate 6. The fingers will rest within the respective recesses 9 and the pick 11 will have its lower end located where it can be brought 60 readily into engagement with one or more of the strings. With the parts thus arranged the player operates the plectrum by oscillating it laterally. As the wrist and hand are supported the player will not tire 65 as quickly as where no rest is provided. The pick 11 can of course be removed and inverted.

Instead of pivotally connecting the arm 4 to the block 1, as shown, a spring tongue 14 70 can be secured at one end within a block 15 and at its other end within an arm 16 corresponding with the arm 4. Thus during the actuation of the plectrum this tongue, formed of spring material, will yield laterally but will at all times properly support the arm.

If desired the hand supporting member of the device can be mounted for lateral tilting and can be made of one or more separate sections tiltable laterally on a rod adapted to oscillate from side to side. Thus the movement of the hand is freer than otherwise.

What is claimed is:

A plectrum including a hand supporting member, means for connecting said member at one end to the body of a stringed instrument for lateral oscillation, a wrist plate at one end of the member, a finger plate at the other end thereof, a pick, and means for detachably connecting the pick to the member and adjacent the finger plate.

In testimony that I claim the foregoing as my own, I have hereto affixed my signature.

JAMES LUCK WARNER.
